UNITED STATES PATENT OFFICE

JOSEPH LEEROY BARNES, OF PITTSBURGH, PENNSYLVANIA

SHUTTER OPERATING MEANS FOR HOODS OF AUTOMOBILES

Application filed December 3, 1930. Serial No. 499,815.

This invention appertains to automobiles, and more particularly to a novel hood construction therefor.

One of the primary objects of my invention is to provide novel means for opening and closing the side doors or louvers of the hood of an automobile in accordance with the temperature of the engine, whereby the louvers or doors can be kept closed during the initial starting of the engine to facilitate the quick heating thereof, and whereby the doors can be opened a greater or less degree as the temperature of the engine increases.

In some makes of automobiles, it has now been proposed to provide hinged side louvers or doors for the engine hood, but no means has been provided for opening and closing the said louvers or doors.

It is therefore another prime object of my invention to provide an automatic means for opening and closing the pivoted doors or louvers in the sides of the engine hood in accordance with the temperature of the engine or the temperature of the liquid used to cool the engine, whereby the best working conditions, in regards to temperature, can be obtained for the engine.

A further salient object of my invention is the provision of means whereby all of the louvers or hinged doors can be simultaneously operated on both sides of the hood, and whereby the sides of the hood can be readily raised or lowered, in making engine repairs and the like, without disturbing said operating means for the louvers.

A still further object of my invention is to provide an improved automobile hood of the above character, which will be durable and efficient in use, one that will be simple and easy to manufacture, and one which can be incorporated with a motor vehicle at a small cost.

With these and other objects in view, the invention consists in the novel construction, arrangement, and formation of parts, as will be hereinafter more specifically described, claimed, and illustrated in the accompanying drawings, in which drawings—

Figure 1 is a top plan view of an automobile hood constructed in accordance with

my invention, parts of the hood being shown broken away and in horizontal section.

Figure 2 is a fragmentary side elevation of an automobile hood showing my invention incorporated therewith, the hood being shown broken away and in section, the section being taken on line 2—2 of Figure 1 looking in the direction of the arrows.

Figure 3 is a fragmentary top plan view partly broken away and in section similar to Figure 1 showing the louvers or hinged doors on one side of the hood in their partially opened position.

Figure 4 is a detail vertical section taken on the line 4—4 of Figure 3 looking in the direction of the arrows.

Figure 5 is a transverse section through the hood of the motor vehicle taken on the line 5—5 of Figure 2 looking in the direction of the arrows, one side of the hood being shown in a raised position.

Figure 6 is a detail fragmentary perspective view illustrating the engagement of the sliding operating wedges with the rollers of the operating rods for the hinged doors or louvers.

Figure 7 is a fragmentary horizontal sectional view illustrating another means for actuating the operating rods for the louvers.

Figure 8 is a view similar to Figure 7 showing the louvers on one side in an open position.

Figure 9 is a detail perspective view illustrating the engagement of one of the actuating cams with the roller of one operating rod.

Figure 10 is a fragmentary longitudinal sectional view illustrating a manual means for operating the sliding wedges or cams for actuating the operating rods for the louvers.

Referring to the drawings in detail, wherein similar reference characters designate corresponding parts throughout the several views, the letter A generally indicates an automobile which can be considered of the type now in general use. As shown, the automobile A is provided with a cowl 15, the radiator 16, and the hood 17 extending from the cowl 15 to the radiator. The hood 17 includes the longitudinally extending hinge rod 18, to which is hingedly connected the com-

panion side sections 19 and 20, which sections each include the top wall or cover plate 21, and the side wall or plate 22, the side plate or wall 22 being pivotally connected as at 23 to the top plate or cover 21.

5 In accordance with my invention I provide the side plate 22 of each section 19 and 20 of the hood 17 with enlarged openings 24, which are adapted to be opened and closed by hinged doors or louvers 25.

10 One of the important features of my invention is the provision of novel means for operating the doors or hinged louvers 25 and as shown in Figures 1 to 6 inclusive I employ a thermostat 30, which can be secured to the inner face of the radiator 16 adjacent to the upper end thereof, namely at the hot water end. This thermostat has connected therewith a cross rod 31, and the cross rod is raised and lowered according to the expansion and 15 contraction of the thermostat 30, the thermostat being expanded and contracted by the temperature of the engine and the water in the radiator, as is well understood by those skilled in the art. The ends of the rod 31 are bent downwardly as at 32 and these ends are provided with feet 33, which are anchored in wedge shaped slide blocks or cams 34. It is to be noted that the upper and lower 20 ends of these cams or slide blocks 34 are beveled as at 35. These blocks are slidably mounted in suitable guide ways 36, which are secured to the inner face of the radiator 16 on each side of its vertical center. Thus with 25 the expansion and contraction of the thermostat 30 the slide blocks 34 will be raised or lowered.

The inner faces of the hinged louvers or doors 24 adjacent to the pivot point thereof, 30 are provided with pivot ears 37 to which are pivotally connected short links 38. The inner ends of these links 38 are pivotally connected to operating rods 39, which extend longitudinally of the hood on each side thereof. These rods 39 can be mounted in guides 39' carried by the hood which prevents sidewise movement of the rods away from the sides of the hood. The forward ends of the operating rods 39 are provided with yokes 40, which rotatably receive anti-friction rollers or spools 41, which are normally urged into engagement with or toward the slide blocks or wedges 34 by means of contractile coil springs 42. The springs 42 have their inner ends anchored to the operating rod 39 and the outer ends secured to the inner sides of the hood 17 adjacent to the forward ends thereof.

By this arrangement the springs 42 normally function to move the operating rod 39 forwardly and consequently, the doors 25 to a closed position, which prevents the entrance of cooling air into the hood from the sides thereof. This permits the quick warming of the engine and as the engine heats and requires cooling air, the thermostat 30 expands

moving the cross rod 31 and the wedges 34 downwardly. The beveled lower faces of the wedges 34 will engage the rollers 41 and push inwardly on the operating rod 39. This movement of the operating rod will swing the louvers or hinged doors open and as the heat of the engine increases further downward movement of the slide blocks will open the doors or louvers 25 further. Upon the stopping of the engine and the contraction of the thermostat 30 the wedge blocks 34 will be raised allowing the automatic closing of the doors, shutters or louvers 25.

5 In Figures 7 to 9 inclusive I have shown a slightly modified form of means for operating the rods 39 and in this instance I provide a thermostat 50, which I preferably locate directly in the interior of the radiator 16 adjacent to the upper end thereof. The expansion and contraction of this thermostat 50 80 operates a bell crank 51, which is rockably mounted at its angle, as at 52, on a bracket 53, which can be riveted or otherwise secured to the inner face of the radiator. As shown, the outer end of the inner arm of the bell crank 51 is connected with the moving part of thermostat, while the outer end of the inner arm is pivotally connected to a cross rod 54. Expansion and contraction of the thermostat 50 85 will rock the bell crank and this movement will be transmitted to the cross rod 54. The cross rod 54 is pivotally connected at its end, as at 55, to swinging cams or cam blocks 56, as clearly shown in Figures 7 and 9. These cam blocks 56 are arranged in a vertical plane 90 and swing in a horizontal plane, being pivotally connected to supporting brackets 57, which can be anchored in any desired way to the inner faces of the radiator 16, adjacent to the opposite sides thereof. Thus swinging movement of these cam blocks 56 into and out of engagement with the rollers 41 of the operating rods 39 will move the rods inward to open the shutters or louvers 25, and upon movement of the cam blocks away from the rollers, the contractile coil springs will function to move the rods 39 forwardly and consequently close said shutters.

10 It is to be noted at this point that the upper ends of the cam blocks 56 are beveled, as indicated by the reference character 57.

I have the upper edges of the cam blocks 56 beveled at 57 and the upper edges of the slide blocks 34 beveled for a purpose, which 110 will now be described.

11 It is essential that the sides of the hood be freely movable so that the same can be raised or lowered to permit convenient inspection of the engine. By providing the operating rods 125 39 and the rollers 41 freely independent of the actuating slide blocks and cam plates, this is permitted. It is to be noted that when the sides of the hood are moved to a lowered position that the rollers will strike the beveled 130

upper ends of the slide blocks or plates as the case may be and thus always be in position.

In Figure 10 I have illustrated a mechanical means for actuating the louvers, and in this form I entirely eliminate the thermostat 50. As shown, I provide a cross rod 60, the ends of which are connected to wedge shaped slide blocks 61 mounted in guide ways 62, for engagement with the rollers 41 of the operating rods 39. So far, this construction is identically the same as that shown in Figures 1 to 6 inclusive. In this form of the invention I provide the cross rod 60 with a vertically disposed threaded feed rod 63, which receives a feed nut 64 anchored in place by a suitable collar 65 connected with the radiator 16. This feed nut 64 is turned by means of a beveled gear 66, keyed or otherwise secured to an operating shaft 67, which extends forwardly from the dash board 68 of the vehicle. The rear end of the operating shaft is provided with an operating crank 69, so that the operator of the vehicle can readily turn the same. The beveled gear 66 meshes with a beveled gear 70 formed on or secured to said feed nut. It is obvious that upon rotation of the shaft 67 that the nut will be turned consequently moving up or down the wedge block 61.

From the foregoing description, it can be seen that I have provided novel means for operating the pivoted shutters or louvers of the sides of an automobile hood.

Changes in details may be made without departing from the spirit or the scope of this invention, but:

What I claim as new is:

1. The combination with an automobile including a radiator and a hood having louvers hingedly connected with the sides thereof, operating rods extending longitudinally of the hood on each side thereof, links pivotally connecting the operating rods with the pivoted louvers, and means for simultaneously operating both of said operating rods, said means including a thermostat located adjacent to the upper end of the radiator, and cams for engaging the operating rods.

2. The combination with an automobile including a radiator and a hood having hinged louvers in the sides thereof, of means for opening and closing said louvers including operating rods arranged longitudinally of the sides of the hood, links pivotally connecting the louvers with the operating rods, rollers carried by the forward ends of the rods, a thermostat arranged adjacent to the upper end of the radiator, a cross rod movable by the expansion and contraction of the thermostat, slide blocks operated by the cross rods and arranged in the path of said rollers.

3. The combination with an automobile including a radiator and a hood having hinged louvers in the sides thereof, of means for opening and closing said louvers includ-

ing operating rods arranged longitudinally of the sides of the hood, links pivotally connecting the louvers with the operating rods, rollers carried by the forward ends of the rods, a thermostat arranged adjacent to the upper end of the radiator, a cross rod movable by the expansion and contraction of the thermostat, slide blocks operated by the cross rods and arranged in the path of said rollers, and contractile coil springs normally urging the rods forwardly and the rollers into engagement with the slide blocks.

4. The combination with an automobile including a radiator and a hood having hinged louvers in the sides thereof, of means for opening and closing said louvers including operating rods arranged longitudinally of the sides of the hood, links pivotally connecting the louvers with the operating rods, rollers carried by the forward ends of the rods, a thermostat arranged adjacent to the upper end of the radiator, a cross rod movable by the expansion and contraction of the thermostat, slide blocks operated by the cross rods and arranged in the path of said rollers, contractile coil springs normally urging the rods forwardly and the rollers into engagement with the slide blocks, and guideways secured to the inner face of the radiator receiving said slide blocks.

5. The combination with an automobile including a radiator and a hood having hinged louvers in the sides thereof, of means for opening and closing said louvers including longitudinally extending operating rods, links hingedly connecting the operating rods with the louvers, a thermostat disposed in the radiator, a bell crank rockably mounted at its pivot point to the radiator, means pivotally connecting one arm of the bell crank to the movable part of a thermostat, a cross rod, means pivotally connecting the other arms to the cross rods, rollers carried by the forward ends of the rods, and horizontally swinging cam plates pivotally connected to the ends of the rods and movable into and out of the path of said rollers.

6. The combination with an automobile including a radiator and a hood having hinged louvers in the sides thereof, of means for opening and closing said louvers including operating rods, links hingedly connecting the louvers with the operating rods, rollers carried by the forward ends of the operating rods, slide blocks carried by the inner faces of the radiator and arranged in the path of the rollers, a cross rod connecting the slide blocks together, a feed screw secured to the cross rod, a rotatable feed nut on the screw anchored to the radiator, and means for rotating the feed nut from the instrument board of the automobile.

7. The combination with an automobile including a radiator and a hood having louvers hingedly connected with the sides thereof,

operating rods extending longitudinally of the hood on each side thereof, links pivotally connecting the operating rods with the pivoted louvers, cams carried by the radiator arranged in the path of the inner ends of the rods for actuating said rods, and means for raising and lowering the slide blocks.

In testimony whereof I affix my signature.
JOSEPH LEEROY BARNES.
